UNITED STATES PATENT OFFICE.

JOSEPH GRACIE WINTER FIELD, OF ALTRINCHAM, ENGLAND, ASSIGNOR TO LINOTYPE AND MACHINERY LIMITED, OF LONDON, ENGLAND, A COMPANY OF GREAT BRITAIN.

DISTRIBUTING MECHANISM OF TYPOGRAPHICAL COMPOSING MACHINES.

Application filed January 27, 1927, Serial No. 163,894, and in Great Britain February 13, 1926.

This invention relates to matrix distributing mechanism of typographical machines such as those known commercially under the trade mark "Linotype" and it has for its 5 object to provide new or improved devices whereby the matrices of two different founts of a given line released from one and the same distributor bar, will automatically distribute themselves each into the magazine 10 appropriate to said fount.

For this purpose the matrices falling from the distributor bar, drop into a vertical throat the walls of which are grooved to form channels which serve to guide the matrices by their ears in a manner similar to that 15 obtaining in the magazines themselves.

The lower end of the throat connects directly with the point of junction of the two entrances appertaining to the magazines appropriate to the two founts to be distributed, 20 said entrances being divided by partition plates into channels corresponding with given channels of the magazines.

The matrices of both of the founts have 25 grooves in one of their side faces the grooves of one fount being parallel with the front and back edges of the matrices and herein termed straight grooves, while those of the other fount are inclined to those edges and 30 these latter are herein termed inclined.

At the above named point of junction of the two entrances, each entrance channel is provided with a pivoted switch or gate which, in normal position, serves to direct 35 matrices having the straight grooves into the upper magazine and which, by matrices having the inclined grooves, is moved clear of said matrices so that these latter are directed into the lower magazine.

40 The invention will best be understood by reference to the accompanying drawings in which:—

Figure 1 is a front elevation of part of the improved distributing mechanism;

45 Figures 2 and 3 are vertical sections showing the manner of distributing matrices into the upper and lower magazines respectively;

Figure 4 is a plan of Figure 2, with parts omitted, and

50 Figures 5 and 6 are views of two matrices of the different founts.

In the arrangement as here illustrated, the matrices on falling from the distributor bar

55 1, drop into a vertical throat 2 the front and rear walls of which are grooved as shown at

3, to form channels with which the ears of the matrices engage so that throughout such engagement said matrices are free to move only in vertical or rectilinear direction.

The vertically channelled throat 2 connects 60 with the before mentioned point of junction of two magazine entrances 4, 5 appertaining to the magazines 6, 7 appropriate to the two founts of matrices to be distributed; the matrices of these two founts are respectively 65 identified by the numerals 8, 9, that is to say the matrices 8 and 9 are distributed into the magazines 6 and 7 respectively, as clearly evident from figures 2 and 3 of the drawings.

70 The entrances 4, 5 are divided by partition plates 10 into channels corresponding with given channels of the magazines 6, 7.

At the above named point of junction of the two magazine entrances 4, 5, which is 75 hereinafter referred to as a junction box, the channels of said entrances are provided with switches or gates 11 all mounted upon a common pivot 12 and each capable of freely moving between adjacent partition plates 10 80 from one to the other of the two terminal positions respectively indicated in Figures 2 and 3. When a switch 11 is in the position in which it is represented in Figure 2, which is regarded as its normal position, it serves 85 to direct the matrices 8 into the magazine 6, and when in the other position as in Figure 3, (which is herein referred to as the variant position) it is removed from the path of the descending matrices which thus are free to 90 fall into the entrance 5 by which they are directed into the magazine 7.

95 The movement of a switch 11 from the normal to the variant position is automatically effected by the matrices 9, and for this purpose each switch 11 is operated by the downwardly extending arm of a so-called switch lever 13 of which, an upwardly extending arm is located in the respective channel of the throat 2 and is provided with a pin 100 or projection 14, see particularly Figure 4, adapted to be engaged by or received in, a groove formed in one side of the matrix, it being explained that all the matrices of both founts have grooves in them and that the lower ends of these grooves occupy the same 105 position in the feet of the respective matrices.

110 The grooves 8^a of the matrices 8 however, differ from the grooves 9^a of the matrices 9

inasmuch as the former, herein termed straight grooves, extend from bottom to top parallelly with the front and back edges of those matrices as shown in Figure 5, whereas the grooves 9^a as shown in Figure 6, incline from front to back.

The levers 13 are pivoted all preferably upon a common rod or wire 15 and the engagement of these levers with the switches 11 is effected by pins 16 fast to the former, underlying the latter, and said levers are moreover provided with weighted arms 17 which serve to restore the levers 13 to their normal position after as hereinafter described, they have been deflected therefrom by the matrices 9. The switches 11 are provided with weighted arms 18 which nearly, but not quite, balance the weight of said switches.

20 When a matrix 8 reaches its respective switch lever 13, the groove 8^a thereof passes freely over the projection 14 of the lever so that the latter is not deflected from its normal position and said matrix travels over 25 the switch 11 and is directed by it into the upper magazine 6; when, however, a matrix 9 reaches its respective lever 13, the inclined groove 9^a thereof acts as a cam on the projection 14 of said lever and moves the latter so as to turn the corresponding switch 11 30 out of the path of this same matrix so that said matrix falls directly into the entrance 5 appropriate to the lower magazine 7 all as clearly shown in Figure 3.

35 The throat 2 and entrances 4, 5 are preferably mounted so that they can be swung backwards from the magazines if and when necessary, and said entrances may be provided with doors or the like, by opening 40 which, access may be had for removing obstructions.

The throat is preferably surmounted by a short partitioned entrance 19 hinged thereto, which can be turned on its hinges for gaining access to the interior of said throat and entrance.

Having described my invention, I declare that what I claim and desire to secure by Letters Patent is:—

50 1. In a typographical composing machine wherein matrices of different founts are automatically distributed according to fount into one or other of two magazines, the combination with a throat through which the matrices descend vertically, two magazine entrances one for each magazine, and a junction box through which both of the magazine entrances communicate with the throat, of a switch movable within the junction box to open and close the communication with the two magazines in alternation, and means actuated by through-grooves arranged lengthwise in the side faces of the matrices as the latter are descending 55 through the throat, for moving the switch 60 to open and close the communication with the two magazines in alternation, and means actuated by through-grooves arranged lengthwise in the side faces of the matrices as the latter are descending 65 through the throat, for moving the switch

from one to another of its terminal positions.

2. In a typographical composing machine wherein matrices of different founts are automatically distributed according to fount 70 into one or other of two magazines, the combination with a throat through which the matrices descend vertically, two magazine entrances one for each magazine, and a junction box through which both of the 75 magazine entrances communicate with the throat, of a switch movable within the junction box to open and close the communication with the two magazines in alternation, and a lever engaging the switch and rocked 80 upon its fulcrum to actuate the switch, by grooves in matrices of one of the two founts to be distributed as the side matrices descend through the throat, the matrices of the other fount having grooves arranged to 85 clear the switch actuating lever in their descent through the throat.

3. In a typographical composing machine wherein matrices of different founts are automatically distributed according to fount 90 into one or other of two magazines, the combination with a throat through which the matrices descend vertically, two magazine entrances one for each magazine, and a junction box through which both of the 95 magazine entrances communicate with the throat, of a switch movable within the junction box to open and close the communication with the two magazines in alternation, and means actuated by grooves in matrices 100 descending through the throat, for moving the switch from one to another of its terminal positions, all the matrices of the two founts being grooved, the grooves of matrices of one fount being inclined to the direction of travel of those matrices through 105 the throat.

4. In a typographical composing machine wherein matrices of different founts are automatically distributed according to fount 110 into one or other of two magazines, the combination with a throat through which the matrices descend vertically, two magazine entrances one for each magazine, and a junction box through which both of the magazine entrances communicate with the throat, of a switch movable within the junction box to open and close the communication with the two magazines in alternation, and means actuated by grooves in matrices descending 115 through the throat, for moving the switch from one to another of its terminal positions, all the matrices of the two founts being grooved, the grooves of matrices of one fount being aligned or parallel with the direction of travel of those matrices through 120 the throat.

5. In a typographical composing machine wherein matrices of different founts are automatically distributed according to fount 125

into one or other of two magazines, the combination with a throat through which the matrices descend vertically, two magazine entrances one for each magazine, and a junction box through which both of the magazine entrances communicate with the throat, of a switch movable within the junction box to open and close the communication with the two magazines in alternation, and a lever 10 engaging the switch and rocked upon its fulcrum to actuate the switch, by grooves in matrices of one of the two founts to be distributed and a projection on the lever engaged by the grooves to effect such switch-actuation.

6. In a typographical composing machine wherein matrices of different founts are automatically distributed according to fount into one or other of two magazines, the com-

bination with a throat through which the 20 matrices descend vertically, two magazine entrances one for each magazine, and a junction box through which both of the magazine entrances communicate with the throat, of a switch movable within the junction box 25 to open and close the communication with the two magazines in alternation, and a three armed lever engaging the switch with one arm, and rocked upon its fulcrum to actuate the switch by the engagement with another 30 of its arms of grooves in matrices of one of the two founts to be distributed, whilst the third of its arms serves to restore the lever to normal position.

In testimony whereof I have affixed my 35 signature hereto.

JOSEPH GRACIE WINTER FIELD.
